UNITED STATES PATENT OFFICE.

ARTHUR E. LEHMANN, OF ST. CHARLES, MISSOURI, ASSIGNOR, BY MESNE ASSIGNMENTS, TO COMMONWEALTH STEEL COMPANY, A CORPORATION OF NEW JERSEY.

CAR END CONSTRUCTION.

1,124,037.

Specification of Letters Patent. Patented Jan. 5, 1915.

Application filed December 15, 1913. Serial No. 806,801.

To all whom it may concern:

Be it known that I, ARTHUR E. LEHMANN, a citizen of the United States, residing at city of St. Charles, State of Missouri, have invented a certain new and useful Improvement in Car End Construction, of which the following is a full, clear, and exact description, such as will enable others skilled in the art to which it appertains to make and use the same, reference being had to the accompanying drawings, forming part of this specification, in which—

Figure 1 is an end elevation of a car underframe and a portion of the superstructure, and showing my improved reinforcing frames applied thereto. Fig. 2 is a horizontal section taken approximately on the line 2—2 of Fig. 1. Fig. 3 is a side elevational view of one of the car end reinforcing frames. Fig. 4 is an end elevational view of a gondola car with a reinforcing frame of my improved construction, and formed in a single piece, applied to the inside of the end wall. Fig. 5 is a side elevational view of the end of a gondola car with the interior reinforcement at the end thereof. Fig. 6 is an end elevational view of a gondola car with a reinforcing frame of my improved construction applied to the exterior of said car. Fig. 7 is a side elevational view of the end portion of a gondola car with the exterior reinforcement applied thereto. Fig. 8 is an end elevational view of a reinforcing frame of my improved construction, the same being combined with the lower portions of the end posts of a box car. Fig. 9 is a horizontal section taken approximately on the line 9—9 of Fig. 8. Fig. 10 is a side elevational view of a reinforcing member of my improved construction, the same being provided with a depending flange which fits directly against the outer face of the end sill or buffer beam of the car underframe.

My invention relates generally to rail-way car construction, and more particularly to the construction of the ends of the cars, the principal object of my invention being to provide a strong and rigid structure which will materially reinforce the ends of the cars and which will effectually resist end shocks and crushing stresses, thereby reducing to a minimum the tendency of car bodies to telescope during collisions.

A further object of my invention is to

provide a reinforcing member preferably in the form of a cast metal skeleton frame which is adapted to be applied to the inside or outside of a gondola or box car, and which frame can be advantageously used in the construction of new cars or for repairing cars which have been in service.

In order to materially strengthen and reinforce the end portions of cars, various metal structures have been devised and are at present in general use, which structures include metal underframes, platforms, buffering sills, one piece end frames and reinforced corner posts, and to further strengthen and reinforce the ends of cars, I propose to provide cast metal skeleton frames located upon the underframe end sill or buffer beam, which frames combine readily with the underframe and end wall construction to form a shock absorbing and resisting structure which materially reinforces and strengthens the extreme ends of the car superstructure.

My improved reinforcing frames are particularly designed for use in connection with blind end cars having either cast steel or built-up underframes.

With the above and other objects in view, my invention consists in certain novel features of construction and arrangement of parts hereinafter more fully described and claimed.

Referring by numerals to the accompanying drawings, 1 designates the buffer beam of a car underframe, and projecting rearwardly from the end portions thereof are the usual side sills 2.

My improved end reinforcing members which are applied to the buffer beam 1 to the sides of the end door opening, are each formed in a single piece, preferably by casting, and each frame comprises a flanged base rail 3, a flanged top rail 4, an inner post or upright 5, an outer post or upright 6, and, an intermediate or upright post 7. Formed integral with the outer end post 6 and arranged at right angles to the plane occupied by the rails 3 and 4, is a vertically disposed plate 8, the lower end of which rests directly upon the end portion of the side sill 2. This side sill is preferably provided with a lug 2^a which forms a shoulder against which the rear lower end of the plate 8 engages, thereby effectually holding the reinforcing member against inward

movement upon the underframe and relieving the rivets which are utilized in attaching the reinforcing member to the underframe, of shearing strains.

6 The upright plate 8 which forms a brace for that portion of the reinforcing member which is located upon the buffer beam, is preferably formed with a marginal flange, and formed integral with the lower portion 10 of said plate and the outer end portion of the bottom rail 3, is a horizontally disposed gusset plate 9. The lower portions of the corner posts of the car body are fixed in any suitable manner directly to the posts or uprights 6 and the forward portions of the plates 8, and the lower ends of said corner posts are fixed in the usual manner to the ends of the buffer beam 1. The posts or uprights 5 at the inner ends of the reinforcing 20 frames are fixed by means of rivets or like fastening devices to the lower portions of the vestibule posts 11, and formed integral with the lower ends of said posts 5 and with the corresponding ends of the bottom rails 3, are forwardly projecting plates 12 which bear upon and are fixed to the buffer beam 1 near the lower ends of said vestibule posts.

30 Car end wall posts 13 between the vestibule posts and corner posts, are fixed in any suitable manner to the intermediate posts 7. The lower portions of the car end sheets 14 overlie and are fixed to the reinforcing frames in any suitable manner, preferably 35 by means of rivets.

Where my improved reinforcing frames are applied to cars which do not require an end door opening, the upper and lower portions of the frames can be connected by 40 cross rails, such as 15, and said rails may be formed integral with the frames or made separate and attached thereto.

In the modified construction illustrated in Figs. 4 and 5, the reinforcing member is in 45 the form of an upright skeleton frame comprising a base member 16, a top rail or member 17, a series of uprights 18, and side sill engaging brackets 19 which project rearwardly from the ends of the skeleton frame. 50 The reinforcing frame thus formed is applied to the inside of a gondola car at the end thereof with the base rail 16 resting upon the end sill or buffer beam of the underframe, with the skeleton frame engaging 55 the inner face of the end wall or sheet of the car body and with the brackets 19 engaging upon and fixed to the side sills of the underframe. Such construction, which is applicable for either new or old cars, materially strengthens and reinforces the end portions of said cars.

In the modified construction illustrated in Figs. 6 and 7, the reinforcement is in the 60 form of an upright skeleton frame 20 which is applied to the outside of the end of a

gondola car, said frame being directly against and being fixed to the end wall of the car with the base rail fixed to the end sill or buffer beam and with the brackets at the ends of the reinforcing frame, engaging 70 upon the end portions of the side sills. This form of reinforcement is applicable for either new or old cars.

In the construction illustrated in Figs. 8 and 9, the reinforcement is in the form of a 75 skeleton frame, the lower rail of which rests upon the end sill or buffer beam of a car having end posts and in this particular construction the vertical members 21 of the reinforcement are preferably made channel-shape in cross section and receive the lower 80 portions of the end posts.

In the modified construction illustrated in Fig. 10, the lower rail of the skeleton frame is provided with a depending flange 22 which, when the frame is applied to the car, engages directly against the outer face of the end sill or buffer beam, and the side sill engaging brackets on the ends of the frame are provided with depending flanges 22^a 90 which engage directly against the ends of the end sill or buffer beam, and the end portions of the side sill.

Reinforcing frames of my improved construction are comparatively simple, can be 95 cheaply produced, are adapted to be combined with various types of cars, and when properly positioned, unite with the underframe and end posts of the car superstructure, to provide a very strong and rigid 100 structure which will resist severe end shocks and crushing stresses due to collisions, thereby materially reducing the tendency of cars to telescope and afford a maximum degree of safety to life and property.

105 It will be readily understood that minor changes in the size, form and construction of the various parts of my improved car end construction can be made and substituted for those herein shown and described, without departing from the spirit of my invention, the scope of which is set forth in the appended claims.

I claim:

1. The hereindescribed car end reinforcing member comprising a skeleton frame adapted to be applied to the end portion of a buffer beam, a bracket integral with the outer end of said skeleton frame, which bracket extends rearwardly from said frame 115 and is adapted to engage the side sill of the underframe, and a gusset plate between the lower portion of the skeleton frame and bracket.

2. The hereindescribed car end reinforcing member comprising a skeleton frame adapted to be applied to the end portion of a buffer beam, a bracket integral with the outer end of said skeleton frame, which bracket extends rearwardly from said frame 125 130

and is adapted to engage the side sill of the underframe, a gusset plate between the lower portion of the skeleton frame and bracket, and a plate integral with the inner 5 end of the skeleton frame, which plate is adapted to engage and be fixed to the buffer beam.

3. The combination with a car underframe and vestibule and corner posts, of reinforcing members arranged on the buffer beam of the underframe to the sides of the end door opening, each of which members comprises a skeleton frame arranged between the vestibule post and corner post, a 15 bracket integral with said skeleton frame, which bracket projects rearwardly from the corner post and rests upon the underframe side sill and a plate integral with the inner end of the skeleton frame, which plate is 20 adapted to engage and be fixed to the buffer beam.

4. The combination with a car underframe, of a pair of reinforcing members applied to the buffer beam of the underframe to the sides of the end door opening, each of which members comprises a skeleton frame adapted to engage the vestibule posts, the corner posts and the intermediate posts of the car end structure, brackets integral 30 with the ends of said skeleton frames, which brackets engage the end portions of the underframe side sills and a plate integral with the inner end of the skeleton frame, which plate is adapted to engage and be fixed to 35 the buffer beam.

5. The combination with a car underframe, of a pair of reinforcing members applied to the buffer beam of the underframe to the sides of the end door opening, each 40 of which members comprises a skeleton frame adapted to engage the vestibule posts, the corner posts, and the intermediate posts of the car end structure, brackets integral with the ends of said skeleton frames, which 45 brackets engage the end portions of the un-

derframe side sills, and gusset plates between the lower portions of the skeleton frames and the brackets.

6. The herein-described reinforcing member for car ends comprising a skeleton 50 frame composed of top and bottom rails and a series of uprights, a vertically disposed bracket integral with the outer one of said uprights, which bracket is arranged at right angles to the rails of the skeleton 55 frame, and a gusset plate integral with the lower portion of said bracket and the bottom rail of the skeleton frame.

7. The herein-described reinforcing member for car ends comprising a skeleton 60 frame composed of top and bottom rails and a series of uprights, a vertically disposed bracket integral with the outer one of said uprights, which bracket is arranged at right angles to the rails of the skeleton 65 frame, a gusset plate integral with the lower portion of said bracket and the bottom rail of the skeleton frame, and a horizontally disposed plate integral with the lower end of the inner one of the uprights of the skele- 70 ton frame.

8. As a new article of manufacture, a cast metal reinforcing member comprising a frame adapted to be positioned on the end portion of a buffer beam or end sill for engaging the lower portion of the car end wall and reinforcing the lower portion of the car end frame, a side sill engaging bracket integral with the end of said reinforcing frame and an integral gusset plate 75 between the lower portions of said frame and bracket.

In testimony whereof I hereunto affix my signature in the presence of two witnesses, this 5th day of December, 1918.

ARTHUR E. LEHMANN.
